PROPORTIONING BURNER

Alexander J. Turpin, Stewart Manor, N. Y., assignor to Hauck Manufacturing Company, Brooklyn, N. Y., a corporation of New York

Application December 12, 1941, Serial No. 422,701

3 Claims. (Cl. 299—140)

The invention relates to mixer and burner apparatus suitable for the intimate mixture and combustion of various liquids, particularly as fuels in a gaseous, liquid, or even powdered-solid state, for example, as in the mixing or atomizing of a combustible oil or gas or powdered fuel with air or steam or with a further combustible gas. The invention has reference more especially to a burner of the type set forth in U. S. Letters Patent #2,219,119, granted October 22, 1940, to Alfred F. Schumann and applicant, assignors to Hauck Manufacturing Company. These burners provide for automatically and accurately proportioning from minimum to maximum capacity all of the primary and secondary atomizing air with reference to the fuel flowing through the burner, and combine a straight-line-flow fuel-control valve with a straight-line-flow air-control mechanism in a single unit.

The present invention has reference to improvements in a burner of this nature; and it has for an object to provide a compact and rugged unit constituted of a minimum number of parts which are readily accessible and removable, as for cleaning or replacement.

A further object of the invention is to insure the maintenance of the different elements in their proper coaxial relationship, particularly in the case of smaller size burners.

In carrying out the invention, the burner body and atomizing fluid nozzle are constituted as a unit; and a member for supplying fuel, including the one half of the fuel-control element, is integral with a back plate designed for sealing the burner body at the end opposite its nozzle outlet.

The nature of the invention, however, will best be understood when described in connection with the accompanying drawing, in which:

Fig. 1 illustrates the novel burner unit in elevation.

Fig. 2 is a longitudinal section therethrough.

Fig. 3 is an end view with the bracket, valve cover, and attached parts removed.

Referring to the drawing, the burner member is shown to comprise a suitable body 10 with integral cylindrical casing 11 affording a longitudinally disposed chamber 12, the casing terminating in a conical discharge tip 13 with axial outlet 14 for an atomizing gaseous medium, as air under requisite pressure. This fluid is to be supplied to the chamber 12 through an inlet 15 in the body with which said chamber is in direct communication.

At the end of the body 10 opposite the outlet 14

5 said body is provided with an opening 16 sealed by a plate 17 which is removably attached thereto as by means of screws 18. Extending axially inwardly into the body 10 and integral with said plate 17 is a duct member 20 axially bored through as at 21 to afford a passageway for the combustible fluid to be mixed with the atomizing medium, the inner end of said duct member extending into the chamber 12. At this end, the duct member is provided with a suitable nozzle 22 which projects beyond said end and has suitable discharge outlets 23.

At the outer end of member 20, the plate 17 provides a seat 25 for a suitable valve piece 26 which operates over a port 27 through the seat, said port communicating with the bore 21 to supply the fluid fuel to the burner. This is introduced into a chamber 28 over port 27 through a supply pipe 29, said chamber being formed between the seat 25 and a cover member 30. The latter is removably attached to the plate 17 as by means of screws 31, and there extends through said cover the operating spindle 32 for the valve piece 26 which is movable thereby over the port 27 to control the supply of fuel to member 20 and its nozzle 22.

20 The said valve piece is operated similarly to the manner disclosed in the aforesaid patent, as through an angularly movable arm 33 and bracket 34, the arm controlling also the flow of atomizing medium so that both are varied simultaneously as the arm 33 is rocked.

25 Operation of the atomizing medium control is effected as follows and from an extension of the arm 33 into the body 10 to provide an adjusting member 35 which is mounted for oscillatory movement between said plate 17 and the juxtaposed end of the body 10. The adjusting member 35 to this end has an inwardly extending sleeve portion 36 which is slotted longitudinally from its inner edge to provide the slot 37. Between this sleeve portion 36 and the duct member 20 is a further sleeve 38 which is movable on said duct member and extends at one end over the nozzle 22 and into the outlet 14, said sleeve having circularly disposed openings 39 to afford communication between the chamber 12 and the interior of the outer end of said sleeve which is located about the nozzle end 22. Said outer end 50 of the sleeve is of conical shape cooperating with the tip 13 to control therewith the area of opening of the outlet 14.

To this end, provision is made to move the sleeve 38 on the duct member 20 and longitudinally thereof from the oscillatory movement of

the adjusting member 35. This may be effected by means of a pin or screw 40 secured to the sleeve 38 and extending radially therefrom into the longitudinal slot 37 so that when the member 35 is oscillated, corresponding rotational movement will be imparted to sleeve 38. This rotary movement is further caused to reciprocate the sleeve 38 through a pin or screw 41 fixed to the rigid duct member 20 and extending radially therefrom into a helical slot 42 of the said sleeve 38, said slot having a longitudinal extension 43 to the outer edge of the sleeve 38 to admit of separation of the said sleeve from the said duct member 20.

The apparatus hereinbefore described affords a very compact and rugged burner construction and one wherein the positions of the control sleeve and the fuel supply member are maintained accurately in their relation to the outlet opening of the discharge tip of the burner body. To separate a part for repair or replacement, the screws 18 are removed and the cover member 30 with plate 17 and duct member 20 with sleeve 38, as well as the adjusting member 35, may be withdrawn from the burner body as a unit. By then removing the other screws 31, cover 30 and attached elements as well as the adjusting member 35 and the sleeve 38 may be separated from the duct member 20, if necessary, as for cleaning the fuel valve and nozzle.

I claim:

1. Burner apparatus of the nature set forth, comprising a body with integral cylindrical casing portion at one end terminating in a conical discharge tip with axial outlet for fluid, said casing having connection with a source of fluid medium; means to seal the body at the opposite end including a plate removably attached to the body thereat, said plate affording a valve seat with port and an integral duct member extending from the plate into the body axially of its cylindrical casing, axially bored through to the said port and having a nozzle element at its inner end, together with a cover member for the seat secured to the said plate, and a control member for varying the port area operable externally of the cover member; a sleeve movably supported on the duct member extending at one end over its nozzle and having openings to afford communication with the said cylindrical casing por-

tion, the sleeve being juxtaposed to the discharge tip thereof to provide a controllable outlet therewith; and means cooperating with the end of said sleeve opposite its tip to rotate the sleeve on and to move it longitudinally of the said duct member.

2. Burner apparatus of the nature set forth, comprising a body with integral cylindrical casing portion at one end terminating in a conical discharge tip with axial outlet for fluid, said casing having connection with a source of fluid medium; means to seal the body at the opposite end including a plate removably attached to the body thereat, said plate affording a valve seat with port and an integral duct member extending from the plate into the body axially of its cylindrical casing, axially bored through to the said port and having a nozzle element at its inner end, together with a cover member for the seat secured to the said plate, and a control member for varying the port area operable externally of the cover member; a sleeve movably supported on the duct member extending at one end over its nozzle and having openings to afford communication with the said cylindrical casing portion, the sleeve being juxtaposed to the discharge tip thereof to provide a controllable outlet therewith; and means to rotate the said sleeve on the duct member and to move the same longitudinally thereof including an adjusting member extending into the body and mounted between the said plate and the juxtaposed end of said body for oscillatory movement therein, said adjusting member having an inwardly extending sleeve portion slotted longitudinally from its inner edge, a pin carried by the movably supported sleeve member extending radially therefrom into the said slot to impart rotary movement from the adjusting member sleeve to the movably supported sleeve, and a pin fixed in the duct member extending radially therefrom and fitting a helical slot of the said movably supported sleeve to cause the same to move longitudinally of said duct member when the adjusting member sleeve is angularly moved.

3. The apparatus of claim 2, wherein the helical slot in the movably supported sleeve has a longitudinal extension to the outer edge of said sleeve.
